CLAIM

I claim, the ornamental design for a door closure with sliding rail, as shown and described.

DESCRIPTION

FIG. 1 is a bottom, perspective view of a door closure with sliding rail, showing my new design;

FIG. 2 is a bottom, perspective view of another embodiment thereof;

FIG. 3 is a bottom, perspective view of another embodiment thereof;

FIG. 4 is a bottom, perspective view of another embodiment thereof;

FIG. 5 is a bottom, perspective view of another embodiment thereof;

FIG. 6 is a bottom, perspective view of another embodiment thereof;

FIG. 7 is a bottom, perspective view of another embodiment thereof;

FIG. 8 is a bottom, perspective view of another embodiment thereof;

FIG. 9 is a bottom, perspective view of another embodiment thereof; and,

FIG. 10 is a top, perspective view of another embodiment thereof.

1 Claim, 10 Drawing Sheets
